DESIGN.

W. MERSEAU.

Stair-Rod.

No. 8,217.

Patented March 23, 1875.

Mr. J. M. Jackson
design for Stair Rods

W. M. Jackson
of Boston

Boston, March 15, 1875.

UNITED STATES PATENT OFFICE.

WILLIAM T. MERSEREAU, OF ORANGE, NEW JERSEY.

DESIGN FOR STAIR-RODS.

Specification forming part of Design No. **8,217**, dated March 23, 1875; application filed March 12, 1875.
[Term of Patent 7 years.]

To all whom it may concern:

Be it known that I, WILLIAM T. MERSEREAU, of Orange, Essex county, New Jersey, have invented and originated a new Design for Stair-Rods, of which the following is a specification:

The nature of my design is clearly shown in the photographic impression making part of this specification, to which reference is made; and consists of a frosted ground-work, upon which are depicted a series of curved figures, each one of which terminates in a rosette. Above the stem of each curved figure

is placed a bifid figure with a dot beneath it, and below the stem of each curved figure is placed a dot with a bifid figure beneath it.

What I claim as new is—

The design for stair-rods, as shown, consisting of a frosted ground-work, upon which are depicted a series of curved figures terminating in rosettes, and the bifid figures and dots.

W. T. MERSEREAU.
